UNITED STATES PATENT OFFICE

130,131

DESIGN FOR A COMBINATION COIN BANK AND PICTURE FRAME OR SIMILAR ARTI- CLE

Robert Edward Pfleger, Cleveland, Ohio

Application June 21, 1941, Serial No. 101,602

Term of patent 7 years

To all whom it may concern:

Be it known that I, Robert Edward Pfleger, a citizen of the United States, residing at Cleveland, in the county of Cuyahoga and State of Ohio, have invented a new, original, and ornamental Design for a Combination Coin Bank and Picture Frame or Similar Article, of which the following is a specification, reference being had to the accompanying drawing, forming part thereof.

Fig. 1 is a front perspective view of a combination coin bank and picture frame, showing my new design;

Fig. 2 is a rear perspective view thereof; and
Fig. 3 is a top plan view.

I claim:

The ornamental design for a combination coin bank and picture frame or similar article, as shown.

ROBERT EDWARD PFLEGER.
